UNITED STATES PATENT OFFICE.

THOMAS J. FLAGG, OF NEW YORK, N. Y.

DESIGN FOR A MADE-UP SCARF.

SPECIFICATION forming part of Design No. 15,830, dated February 17, 1885.

Application filed September 20, 1884. Term of patent 7 years.

To all whom it may concern:

Be it known that I, THOMAS J. FLAGG, of the city, county, and State of New York, have invented a new and original Design for a Made-Up Scarf for Men's Wear; and I do hereby declare that the following is a full and exact description thereof, reference being had to the accompanying drawing, and to the letters of reference marked thereon, making 10 a part of this specification.

My design involves as its principal feature the configuration of the outer apron, S, of the scarf.

It consists of the two diverging upper lines 15 A B and A C, of unequal length, forming an angle, A, more or less acute, the two re-entrant lines B D and C E, also of unequal length, and which terminate at opposite points, D and E, equidistant from and at a right angle to an 20 imaginary line, x x, drawn centrally through the length of the scarf, and the two lateral lines D F and E G, of equal length, and which are about parallel to each other and to the central line, x x.

25 The form of the lower end of the scarf between the points F and G is not an essential feature of this design, and may therefore be varied to include either a broken line terminating in an angle, H, as shown by the positive lines, or a curved or a straight line, as indicated by the dotted lines in the drawing.

30 The lines and angles A G, C E, and E G define one side of the scarf, and the design is completed by the extension of the line D B to K, making the line D K equal in length to 35 the opposite line, E C, and by a lateral line,

K L, which is of the same length as the opposite lateral line, C A, and converges from K toward the central imaginary line, x x, at about the same angle, and by a top line from L to the angle A, and an inner line, L M, which, extending from the angle L to the point M, at which the line A B intersects the central line, x x, of the scarf, completes the definition of the outlines of the center piece, U, and inner 45 apron, T, of the scarf.

I claim as my invention—

The design for a made-up scarf herein shown and described, which consists of the two diverging lines A B and A C, of unequal length, 50 forming an angle, A, more or less acute, the two lines B D and C E, converging from the lower extremities of the lines A B and A C, the approximately-parallel lower lateral lines D F and E G, of equal length, extended from the 55 lower extremities of the lines B D and C E, and which, connected at their lower ends by a straight or curved or broken line, complete the outline of the outer apron, S, of the scarf, in combination with the line B K, forming a 60 right extension of the line B D, the upper side line, K L, top line, L A, connecting the two latter, and the inner line, L M, which define the inner apron, T, and center piece, U, of the scarf, and complete its configuration. 65

In testimony whereof I have signed my name to this specification in the presence of two subscribing witnesses.

THOMAS J. FLAGG.
